CABINET FOR ELECTRONIC EQUIPMENT

William F. Dalton, Hopewell Junction, and Arnold M. Davis, Walter F. Kraus, and Clarence F. Graser, Poughkeepsie, N.Y., assignors to International Business Machines Corporation, New York, N.Y., a corporation of New York

Filed Oct. 10, 1961, Ser. No. 67,034

Term of patent 14 years

(Cl. D26—5)

FIG. 1

FIG. 2

FIG. 1 is a front perspective view of a cabinet for electronic equipment showing our new design.

FIG. 2 is a perspective view of the rear and right hand side thereof.

The characteristic features of our design reside in the inverted T configuration, the shadow box enclosure extending from front to back for housing a portion of the electronic equipment, the ventilating louvers in the front and back of the base and the setback at the front and rear of the base of the upright portion of the unit all as shown.

We claim:

The ornamental design for a cabinet for electronic equipment substantially as shown and described.
